STEAM GENERATOR AND PROCESS

Original Filed July 18, 1929

UNITED STATES PATENT OFFICE

JOHN E. BLACK, OF RUMSON, NEW JERSEY, ASSIGNOR TO THE BABCOCK & WILCOX COMPANY, OF BAYONNE, NEW JERSEY, A CORPORATION OF NEW JERSEY

STEAM GENERATOR AND PROCESS

Application filed July 18, 1929, Serial No. 379,145. Renewed June 3, 1932.

This invention relates to a steam generator by means of which steam is produced and superheated. The temperature of the superheated steam is maintained constant by heating the steam before it reaches the superheater by means of latent heat of condensation of a fluid that has a higher boiling point than water and regulating the amount of such heating.

In the accompanying drawing there is illustrated diagrammatically one type of steam generator and accessory apparatus for practicing the invention.

In the drawing reference character 1 indicates a steam and water drum of a boiler of the Babcock & Wilcox type, having nipples 2 connecting the water space of the drum 1 to downtake headers 3. A bank of inclined tubes 4 connects the downtake headers 3 to uptake headers 5. Circulating tubes 6 lead from the upper ends of the headers 5 to the steam and water drum 1.

A pipe 7 leads from the steam space of the drum 1 to a steam coil 8 located in a container 9, and a pipe 10 leads from the coil 8 to the inlet header 11 of a superheater 12 from the outlet header of which a pipe 13 leads to a steam main or steam turbine (not shown).

A gas outlet from the boiler furnace extends to the flue 14 in which an economizer may be located.

Furnace wall tubes 15 connected to the lower header 16 have their upper ends extending into a vapor and liquid drum 17. A return pipe 18 leads from the liquid space of the drum 17 to the circulating pump 19 that is connected to the header 16.

A pipe 20 leads from the upper portion of the drum 17 and is provided with a valve 21 that is controlled by a thermostat 22 located in the superheated steam pipe 13. The thermostat 22 is connected by means of the connection 23 to the thermostatically operated valve controlling device 24 for the valve 21. The pipe 20 leads into the container 9 and a pipe 25 leads from the lower portion of this container into a receptacle 26 from the lower portion of which a pipe 27 leads to a centrifugal pump 28 driven by a turbine

29 that receives steam through a pipe 30 that is provided with a valve 31 controlled by a float 32 in the receptacle 26. A pipe 33 leads from the outlet of the pump 28 to the drum 17.

A pipe 34 leads from the pipe 20 to a steam reheater 35 for reheating steam between stages of a turbine. This pipe is provided with a thermostatically controlled valve 36. Exhaust steam from a stage of the turbine enters the reheater tubes 37 in the reheater through a pipe 38 and the reheated steam passes out through the pipe 39 to the next stage of the turbine. A thermostat 40 in the pipe 39 controls the valve 36. A pipe 41 leads from the lower side of the reheater 35 to the receptacle 26.

A branch pipe 42 provided with a pressure regulator and non-return valve 43 leads from the pipe 34 to the coil 44 inside of the drum 1. A pipe 45 leads from the coil 44 to the receptacle 26.

The operation is as follows:

Material that has a boiling point higher than that of water, such as diphenyl oxide for example, is introduced into the tubes 15 in an amount sufficient to bring the upper level of the material into the drum 17, when the system is being operated under normal conditions, and feed water is introduced into the steam boiler in the usual way to fill the same approximately to the level indicated in the drum 1. Part of the heat of the products of combustion is used for generating steam and a part of the heat is used for heating the tubes 15. The heat received by the tubes 15, mainly radiant heat, generates vapors in the high boiling material. High boiling vapors pass through the pipe 20 into the container 9 surrounding the coil 8. The steam passing from the drum 1 is first heated by the latent heat of condensation of the high boiling vapors in the container 9 and then passes through the superheater 12 and out through the outlet pipe 13. The thermostat 22 regulates the amount of high boiling vapors that pass into the container 9 by controlling the valve 21, thereby regulating the temperature of the steam leaving the coil 8 in the container 9 and maintaining the temperature of the su-

perheated steam leaving the superheater 12 substantially constant. When the temperature of the superheated steam rises, the thermostat decreases the amount of vapors passing through the pipe 20 and vice versa. Condensates from the high boiling vapors pass through the pipe 25 into the receptacle 26 in which an approximately constant level is maintained by the float 32 regulating the speed of the turbine 29 which drives the centrifugal pump 28 to force the condensates into the drum 17.

High boiling vapors also pass through the pipe 34 into the reheat 35, the amount thereof being regulated by the thermostat 40. The vapors give up heat of condensation to reheat steam between stages of a turbine. The condensates therefrom pass through the pipe 41 into the receptacle 26. When there is an excess of vapors of high boiling point fluid generated in the tubes 15 over that required for the heating of steam in the coil 8 and superheating of steam in the steam reheat 35, the pressure relief valve 43 opens admitting the vapor into the coil 44 located in the water space of the steam and water drum 1, thus condensing these vapors and generating steam in this drum. The condensates pass from the coil 44 through the pipe 45 into the receptacle 26.

A certain level of liquid is maintained in the receptacle 26 by means of the float 32 controlling the speed of the turbine 29 that drives the pump 28 to force the condensates through the pipe 33 into the drum 17.

By means of this invention, the temperature of superheated steam leaving a steam generator can be maintained constant by adding heat to the steam before it reaches the superheater by means of the heat of condensation of a fluid having a boiling point higher than that of water. While diphenyl oxide is stated to be a suitable substance, the invention is not limited to this particular substance, but is applicable to any substance having the desired properties. Also while the invention has been described in connection with a boiler of the Babcock & Wilcox type, it will be understood that it is equally applicable with other types of boilers.

I claim:

1. A vapor generator including a furnace, independent fluid circulating systems receiving heat from said furnace, one having heat absorbing surface containing a saturated vapor at a higher temperature and lower pressure than the other, the two systems being in thermal transfer relation in at least one location, and a control actuated by the fluid in one system for regulating the heat transfer between systems irrespective of the furnace temperature.

2. A vapor generator including a furnace, independent fluid circulating systems receiving heat from said furnace, one having heat

absorbing surface containing a saturated vapor at a higher temperature and lower pressure than the other, the two systems being in thermal transfer relation to produce dry fluid in the system of lower generating temperature, and controlling means actuated by the physical characteristics in one system for regulating the heat transfer between systems irrespective of the furnace temperature.

3. A vapor generator including a furnace, independent fluid circulating systems receiving heat from said furnace, one having radiant heat absorbing surface and containing a saturated vapor at a higher temperature and lower pressure than the other, and the two systems being in heat transfer relation at several locations, and a temperature control actuated by the fluid in one of said systems for regulating the heat transfer between systems at one of said locations irrespective of furnace temperature.

4. A vapor generator including a furnace, independent fluid circulating systems receiving heat from said furnace, one having radiant heat absorbing surface and containing a saturated vapor at a higher temperature and lower pressure than the other, the two systems being in heat transfer relation at several locations, and a fluid condition actuated control regulating the heat passing from the one system to the other whereby the vapor quality of one system is controlled by the other system irrespective of furnace temperature.

5. A vapor generator including a furnace, independent fluid circulating systems receiving heat from said furnace, one having radiant heat absorbing surface and containing a saturated vapor at higher temperature and lower pressure than the other, the systems being in heat transfer relation at locations producing saturated and superheated vapor in the higher pressure system, and a temperature control actuated by the temperature of the higher pressure vapor to regulate heat transfer between the two systems irrespective of furnace temperature.

6. A vapor generator including a furnace, independent fluid circulating systems receiving heat from said furnace, one having radiant heat absorbing surface and containing a saturated vapor at higher temperature and lower pressure than the other, the systems being in heat transfer relation at locations producing saturated and superheated vapor, and fluid condition actuated controlling means regulating the heat transfer at the locations producing unsaturated vapor irrespective of furnace temperature.

7. A vapor generator including a furnace, independent fluid circulating systems receiving heat from said furnace, one having radiant heat absorbing surface and containing a saturated vapor at a higher temperature and lower pressure than the other, a primary

superheater heated by the low pressure vapor, a secondary superheater the outlet temperature of which controls the heat added in the primary superheater irrespective of furnace temperature, and a condenser in the system of lower pressure exchanging heat to generate vapor in the system of higher pressure.

8. A vapor generator including a furnace, independent fluid circulating systems receiving heat from said furnace, one having radiant heat absorbing surface and containing a saturated vapor at a higher temperature and lower pressure than the other, a primary superheater heated by the low pressure vapor, a secondary superheater the outlet temperature of which controls the heat added in the primary superheater irrespective of furnace temperature, a condenser in the system of lower pressure exchanging heat to generate vapor in the system of higher pressure, and a reheater also receiving heat from the low pressure vapor.

9. The method of steam generation which comprises establishing combustion of fuel to provide radiant heat and hot flue gases, locating heat absorbing surface of a primary high boiling point fluid circulating system in the zone of radiant heat, subjecting a secondary fluid of totally different physical characteristics to the heat of the flue gases to reduce the temperature of the flue gases, and then transferring at a different location the heat accumulated by said primary fluid to said secondary fluid, and regulating heat transfer irrespective of the temperature of combustion by the temperature of one of the fluids.
